UNITED STATES PATENT OFFICE.

JAKOB ADSER JAKOBSEN, OF ESBJERG, DENMARK.

LIFE-SAVING APPARATUS.

971,273.

Specification of Letters Patent. Patented Sept. 27, 1910.

Application filed April 29, 1908. Serial No. 429,932.

To all whom it may concern:

Be it known that I, JAKOB ADSER JAKOBSEN, a subject of Denmark, residing at No. 25 Smedegade, in the city of Esbjerg and 5 Kingdom of Denmark, have invented certain new and useful Improvements in Life-Saving Apparatus, of which the following is a specification.

This invention relates to a life saving apparatus for lowering persons from burning buildings. The apparatus, which is adapted to be used in connection with a belt provided with a hook and a rope having a ring at each end for fastening the rope to the 10 upper part of the window frame, comprises a pulley-like block, which consists of two halves and slides along the rope or through which the rope slides, the block being provided with a pair of arms by means of 15 which the halves of the block may be 20 pressed more or less together about the rope, thus determining the speed of the descent.

The drawing shows the sliding block.

Figures 1 and 2 show the two halves seen 25 from the inside. Fig. 3 is a cross section through the entire block and Fig. 4 is a side elevation of the block.

Each of the halves has two shafts *a* and *b*, each carrying one or two balls *c*, so that the 30 rope *d*, when the block is put together, will run at two places between the balls; the balls may be arranged as shown in the drawing which shows one half provided with two balls on the upper shaft, and one on the 35 lower shaft, while the other half has one ball on the upper shaft and two on the lower shaft. At the top and at the bottom each of the halves has a strap *e* and a semi-cylindrical recess *f*, in which the rope runs 40 freely.

When both halves are placed about the rope, they are united by a strap *g* forming at each end the pivot for an arm *h*. The arms *h* have at each side a projection *k* so 45 that they will press the halves of the block against the rope when moved toward each other. The form of the halves of the block may vary, for instance the halves may be cup-shaped with holes for the strap *g* or 50 they may consist of three bands, two of them carrying the shafts, while the third is surrounded by the strap *g*.

When using the apparatus I suspend the rope with one of the end-rings upon a hook at the upper part of the window-frame, I 55 put on the belt and hook its hook in the lower straps *e*. Then I take hold of the arms *h* (which may also be adapted to be held with one hand) and slide down along the rope. The more the arms are pressed 60 together, the slower the descent. If children or delicate persons are to be lowered, the rope is fastened to the belt and the sliding block is secured to the window frame; thus a person standing at the window may control the speed; if several persons are to be lowered it is unnecessary to draw the rope back through the slide-block each time, as both ends of the rope and the block are congruent, so that only these ends are changed 65 70 and the arms *h* turned. The rope may be held out from the wall by an arm or the like or by making the hook, on which the rope or the block is suspended, sufficiently long.

Having thus described my said invention 75 what I claim and desire to secure by Letters Patent is—

1. A fire-escape comprising, in combination with a rope, a block consisting of two cup-shaped members, suspending means for 80 said block arranged at one end thereof and means at the opposite end of the block for securing to the person to be lowered, a pair of transverse shafts carried in spaced relation by each of said members, a pair of 85 balls carried by one shaft of each member and disposed in close proximity to each other, a ball carried by the other shaft of each member and arranged to aline with the space between said pair of balls, the balls of 90 the two members engaging on opposite sides of the rope, means projected through each of the members, and other means pivoted to the projecting ends of said last named means and having portions to engage the 95 backs of the members to move the latter toward the rope.

2. A fire-escape, comprising, in combination with a rope, a block consisting of two opposed members, two sets of rollers in each 100 member engaging opposite sides of the rope, an element projected through said members, an arm pivoted to each end of said element, projections formed on each arm to bear

against the backs of the members, said arms being reversible so as to be capable of operation from either end of the block, and suspending means carried at each end of the 5 block, said block being reversible so as to be capable of having its ends interchangeably used.

In testimony whereof I have signed my name to this specification in the presence of two witnesses.

JAKOB ADSER JAKOBSEN.
